UNITED STATES PATENT OFFICE.

WARNER B. COOKE, OF JENKINTOWN, PENNSYLVANIA, ASSIGNOR TO
WILLIAM WHARTON, JR., & COMPANY, INCORPORATED, OF PHILA-
DELPHIA, PENNSYLVANIA, A CORPORATION OF PENNSYLVANIA.

RAILWAY-CROSSING STRUCTURE.

SPECIFICATION forming part of Letters Patent No. 786,193, dated March 28, 1905.

Application filed December 21, 1904. Serial No. 237,808.

To all whom it may concern:

Be it known that I, WARNER B. COOKE, a citizen of the United States, residing at Jenkintown, Pennsylvania, have invented certain Improvements in Railway-Crossing Structures, of which the following is a specification.

The object of my invention is to provide a railroad-crossing structure of great strength and durability, as fully described hereinafter, reference being had to the accompanying drawings, in which—

Figure 1 is a plan view of my improved railroad-crossing. Fig. 2 is a transverse section on the line 2 2, Fig. 1. Fig. 3 is a detached view of one of the intersection body portions of Fig. 1. Fig. 4 is a view of a modification of my invention.

A A, Fig. 1, are the intersection body portions of the crossing, preferably of manganese steel or other hard metal. Each body portion has an arm a , to which is attached a track-rail B, an arm a' , to which is attached a track-rail C, and two extended arms a^2 and a^3 , which abut the extended arms of other intersection body portions A, as clearly illustrated in Fig. 1, which illustrates a single track crossing a single track. Each intersection portion A is grooved at e and e' to allow for the passage of the flanges of the car-wheels, the groove e' crossing the groove e at the proper angle.

The arms a^2 a^3 are in alignment with the tread-surface of the rails B B, while the arms a^3 a^3 are in alignment with the tread-surface of the rails C C, and in order to provide a continuous surface for the tread of the car-wheels the body portions A A are recessed on the outer side of the arms a^2 and a^3 , and bridge-rails D D are mounted in said recesses and secured to the outer side of said arms, as shown in Fig. 1. The outer portion of the tread of the car-wheels runs upon the bridge-rail D, and in this way the joint between the abutting arms has no effect whatever upon the smooth passage of the wheels. The bridge-rail D in addition to this function greatly

strengthens the structure at the joint between the arms.

A guard-rail F runs parallel with the arms a^2 and is secured thereto, being separated from the arms by suitable filler-blocks or otherwise, thus forming the groove for the car-wheel flanges. The guard-rail F likewise spans the joint between the two arms, and thus it also adds greatly to the strength of the crossing. On the outer ends of the crossing structure are guard-rail sections F', which are in line with the guard-rails F.

The bridge-rails and guard-rails may be attached to the intersection body portions by bolts or any other suitable devices, and the structure may be supported on bed-plates or other foundations without departing from the main features of my invention.

In the cross-section shown in Fig. 2 I have illustrated a filler-piece G, forming the base of the groove between the arms and the guard-rail F; but this may form a part of the intersection body portion or a part of the guard-rail, as desired.

In Fig. 4 I have illustrated a modification of the invention, in which the arms a^4 of the intersection body portions A' are recessed on the inner side for the reception of the bridge-rail D'.

The bridge-rails in both forms of the crossing shown may be made of manganese steel or other hard metal, if desired.

I claim as my invention—

1. The combination in a railroad-crossing, of two intersection body portions, each having intersecting grooves for the wheel-flanges and each having an arm, the said arms, when the portions are in place, abutting one another, with a bridge-rail running parallel with the said arms and bridging the joint between the arms, the arms and bridge-rail together forming a continuous bearing-surface for the tread of the car-wheels, substantially as described.

2. The combination in a railroad-crossing, of two intersection body portions, each having intersecting grooves for the wheel-flanges

and each having an arm forming a continuation of a track-rail, and the arms of the two portions abutting each other, with a bridge-rail secured at one side of the said arms and bridging the joint between the arms, substantially as described.

3. The combination in a railroad-crossing, of two intersection body portions, each having intersecting grooves for the wheel-flanges, 10 and each having an arm forming a continuation of a track-rail, the said arms abutting each other, a bridge-rail secured at one side of the said arms and bridging the joint between the arms, with a guard-rail situated on 15 the inner side of the two arms, substantially as described.

4. The combination in a railroad-crossing, of two intersection body portions, each having intersecting grooves for the wheel-flanges, 20 and each intersection portion having two arms abutting arms of other intersection portions of the crossing, with bridge-rails secured to the arms and bridging the joints between the arms, the arms and bridge-rail together 25 forming a continuous bearing-surface for the tread of the car-wheels, substantially as described.

5. The combination in a railroad-crossing, of two intersection body portions, each having intersecting grooves for the wheel-flanges, 30 and each body portion having an arm abutting the arm of the other body portion, a

bridge-rail mounted at one side of said arms and bridging the joint between the arms, a guard-rail mounted on the inner side of the 35 arms, and means for securing the parts together, substantially as described.

6. The combination in a railroad-crossing, of two intersection body portions, each body portion having an arm abutting the arm of the 40 other body portion, a bridge-rail mounted at one side of said arms and bridging the joint between the arms, a guard-rail extending across the joint between the arms, and means for securing the parts together, substantially as described.

7. The combination in a railroad-crossing, of two intersection body portions of manganese steel or other hard metal, each body portion having an arm abutting the arm of the 50 other body portion, a bridge-rail mounted at one side of said arms and bridging the joint between the arms, a guard-rail extending across the joint between the arms, and means for securing the parts together, substantially 55 as described.

In testimony whereof I have signed my name to this specification in the presence of two subscribing witnesses.

WARNER B. COOKE.
